UNITED STATES PATENT OFFICE.

BIRGER BARK, OF CHICAGO, ILLINOIS, ASSIGNOR TO THE BRUNSWICK-BALKE-COLLENDER COMPANY, OF OHIO.

DESIGN FOR A BAR-FIXTURE.

SPECIFICATION forming part of Design No. 23,511, dated July 24, 1894.

Application filed June 25, 1894. Serial No. 515,701. Term of patent 7 years.

To all whom it may concern:

Be it known that I, BIRGER BARK, a citizen of the United States, residing at Chicago, in the county of Cook and State of Illinois, have invented a certain new and useful Design for Bar-Fixtures, of which the following is a description, reference being had to the accompanying drawing, forming part of this specification.

- o My newly invented design, fully illustrated in the accompanying drawing, relates to the back-bar of a set of bar fixtures, said back-bar consisting as usual of the long rectangular base containing the closets and drawers, whose top forms the back counter or side-board and upon which rests the ornamental framework which surrounds the large rectangular mirror which occupies the large middle space of the back wall of the bar.
- o The novelty of my design resides in this ornamental framework, the front side of the base containing the closets and drawers being usually largely hidden from view by the front counter when the set of fixtures is in use.
- o Resting upon the top of the sideboard near each end is a pair of brackets having vertical rear sides abutting against or joined to the main back wall of the fixture. The front sides of the brackets are suitably shaped at their lower ends to form bases or feet, and from these base-portions the faces of the brackets incline upwardly and outwardly to their upper ends which terminate in horizontal turned pieces. Resting upon each pair of brackets is a horizontal plate or shelf of a width corresponding to the depth of the upper ends of the brackets, so that the rear edge of said shelf abuts against the back wall of the fixture while its forward edge is approximately flush with the turned pieces at the upper ends of the brackets. The brackets of each pair are at such distances apart relative to their height that with the shelves resting upon them they form an alcove having an approximately square rear wall, in which is fitted a mirror surrounded by suitable molding. The outer brackets of each pair stand some distance from the ends of the sideboard and the spaces between their outer sides and the ends of the sideboard, at the rear sides of the brackets and board, are filled in with

bracket-plates having curved outer edges and ornamented with scroll-work.

Resting upon the shelf supported by each pair of brackets are two vertical columns, one immediately over each bracket. These columns are rectangular in cross-section, have plain sides, and ornamented rounded front corners. Resting upon the upper ends of the columns of each pair is a horizontal cap-piece or capital having an ornamented front fascia and provided with narrow moldings around its upper and lower edges. Its opposite ends terminate in horizontal turned pieces having rosettes upon their front ends. The rear wall of the rectangular recess inclosed by the columns of each pair and the shelf below and cap-piece above the same is occupied by a mirror.

The middle space of the fixture between the two pairs of columns is occupied by a large rectangular mirror surrounded by a narrow molding, that along its lower edge being all that separates it from the top of the sideboard, so that small glasses and other small objects resting upon the latter will be reflected in the mirror.

Resting at its opposite ends upon the cap-pieces of the two pairs of columns is the entablature of the structure, composed of a lower main portion or frieze, a cornice around the upper edge of the same, and a pediment above the cornice. The body or frieze portion of the entablature is rectangular in cross-section, or apparently so, its exposed opposite ends being rectangular, and of a depth corresponding to the depth of the columns and their cap-pieces, so that the large central mirror forms the rear wall of a recess inclosed by the columns at each side, the entablature above and the sideboard below. The forward corners of the frieze are provided with conventional ornaments, somewhat resembling flour-do-lis, and scrolls beneath the same, and its front face contains a series of substantially circular recesses filled with mirrors or reflecting surfaces. The recesses in the middle portion of the frieze, above the large mirror, are separated equal distances from each other and between them are raised vertical panels upon the surface of the frieze. The two end recesses are somewhat removed

from the adjacent middle recesses above referred to, being located approximately over the middle of the cap-pieces of the columns, and they are separated from the adjacent recesses of the middle series by ornaments upon the surface of the frieze corresponding to those upon its corners.

The upper edge of the frieze is surrounded by a heavy molding or cornice, and above the latter is a pediment, having a conventional ornament at its middle, and provided at its opposite ends with laterally projecting curved or beak-shaped portions, having beaded edges, ornamented upon their faces with scroll-work and terminating at their points in circular turned disks. These lateral projections of the pediment extend some distance beyond the ends of the entablature, to approximately the vertical planes of the ends of the side board, and are adapted to form supports for hanging lamps at the opposite ends of the fixture.

In rear of the front face of the pediment at each end are vertical plates resting upon the ends of the cornice co-incident with the ends of the body portion of the entablature beneath.

The distinguishing feature of the design

consists in the two pairs of brackets resting upon the sideboard near its opposite ends, the horizontal plates or shelves resting upon the brackets, the two pairs of rectangular columns resting upon said shelves and having plain sides and ornamented corners, the cap-pieces resting upon the columns, the entablature resting at its opposite ends upon the cap-pieces and having its frieze provided with the series of recesses containing the mirrors or reflecting surfaces, the pediment surmounting the entablature and having the laterally projecting curved extensions at each end, the large rectangular mirror inclosed between the two pairs of columns at its opposite ends and between the entablature and sideboard above and below it, and the mirrors forming the rear walls of the recesses or alcoves between the brackets and columns of each pair.

Having thus fully described my invention, I claim—

The design for a bar fixture, substantially as herein shown and described.

BIRGER BARK.
